(57) **CLAIM**

The ornamental design for a foot shaped carabiner, as shown and described.

DESCRIPTION

FIG. 1 is a top or bottom plan view, which are mirror images, of my new design for a foot shaped carabiner.

FIG. 2 is a right side elevation view of the carabiner shown in FIG. 1.

FIG. 3 is a left side elevation view of the carabiner shown in FIG. 1.

FIG. 4 is a front elevation view of the carabiner shown in FIG. 1.

FIG. 5 is a rear elevation view of the carabiner shown in FIG. 1; and,

FIG. 6 is a top perspective view of the carabiner shown in FIG. 1.
